UNITED STATES PATENT OFFICE.

SIMEON S. JACKSON, OF HYDE PARK, MASSACHUSETTS, ASSIGNOR TO THE STAFFORD COMPANY, OF BOSTON, MASSACHUSETTS, A CORPORATION OF MASSACHUSETTS.

FEELER MECHANISM FOR LOOMS.

Application filed June 15, 1922. Serial No. 568,511.

To all whom it may concern:

Be it known that I, SIMEON S. JACKSON, a subject of Great Britain, residing at Hyde Park, Boston, in the county of Suffolk, State of Massachusetts, have invented a certain new and useful Improvement in Feeler Mechanisms for Looms, of which the following is a specification, reference being had therein to the accompanying drawings.

The invention has relation, in general, to the depletion-detecting devices or mechanisms, commonly termed weft or filling-feeler mechanisms, which are employed in looms for the purpose of forestalling complete exhaustion of the supply of weft or filling contained in the working shuttle upon the lay of a loom. These mechanisms are usually contrived to indicate or call a change in the working of the loom, upon detecting that the progressive depletion of the said supply has reached a stage decided upon as a minimum. The said change involves in some cases automatic replenishment of the working supply of weft or filling, in others, stoppage of the loom alone.

The invention has relation more especially to filling-feeler mechanisms of the measuring class. A filling-feeler of this class is arranged to call the predetermined change in the operation of the loom when, through its measuring action, it has detected that the residue of weft or filling upon the bobbin or other filling-carrier within the shuttle has been reduced to the predetermined minimum thickness at the point where the measuring action takes place.

The object of my invention is to provide an improved mechanism of the class just mentioned, which shall be accurate in its measuring of the weft or filling, certain and reliable in its action of calling a change at the correct time, formed of few parts, and simple in construction.

My invention consists, briefly, in a filling-feeler mechanism for looms comprising, essentially, a controller for the means for calling a change, a reciprocating filling-engaging member, a horizontally-swinging datum-surface engaging member mounted on a pivot upon the filling-engaging member and having a so-called transmitting arm, and a control-lever, which may be a bell-crank, mounted to rock or swing upon a pivotal axis, usually in connection with the feeler-stand, having one arm which controls

the said controller and a second arm which is engaged by the said transmitting arm, along which the latter arm slides idly while sufficient weft or filling remains upon the shuttle, and against which said transmitting arm acts to move the control-lever to bring about action of the controller to call a change, when depletion of the supply of weft or filling within the shuttle allows the datum-surface engaging member to be rotated through engagement of the datum-surface therewith. The datum-surface utilized may be the front surface of the shuttle-body, or the front surface of the shuttle-box front.

The drawings show an illustrative embodiment of my invention.

In the drawings,—

Fig. 1 is a top view of certain parts at one side of a loom, showing the said illustrative embodiment of my invention mounted in operative position upon its stand at the corresponding end of the breast-beam, the lay being back and the parts of the feeler-mechanism being in their normal positions.

Fig. 2 is a side elevation of the said parts, partly in section on line 2, 2, of Fig. 1.

Fig. 3 is a front view of the feeler-mechanism and associated parts of Figs. 1 and 2.

The different views of the drawings show only small portions of the breast-beam 1 and lay-beam 2 of a loom, 3 being the front plate of the shuttle-box upon that end of the lay-beam which is adjacent the feeler-mechanism, and 4 a shuttle occupying the said shuttle-box. The said front-plate and the front wall of the shuttle have the usual openings 3^a, 4^a, to permit entrance of the filling-engaging portion 5 of the feeler-mechanism as the lay beats up, to provide for contact between the said filling-engaging portion 5 and the filling-mass 6 upon the filling-carrier 7 occupying the shuttle 4.

At 8 is a feeler-stand, it being attached to the outer end of a main supporting stand 9 extending outward from the breast-beam. At 5 is a slide constituting in this instance the filling-engaging member or element, arranged, etc., to receive against its rear end the pressure of the wound mass 6 of weft or filling contained within the shuttle 4. At 8 is a guideway provided upon the feeler-stand, in which the slide 5 is placed and within which it is adapted to reciprocate in the feeling action. At 5^x is the usual

forwardly-extending reduced extension or tail of the slide 5, working in a hole through an upstanding portion 8^b of the forward part of stand 8. At 8^c is the usual cap or cover-plate bridging the guideway, holding the slide down therein, and secured in place by screws 8^d, 8^d. The spring-tension by which the filling-engaging member or element 5 is held normally in its rearward position, and is returned to that position after having been pushed forward in a feeling action by the shuttle-contained weft or filling as the lay beats up, is applied in the illustrated instance by means of an expanding spiral spring 10 surrounding the reduced forward extension 5^x of the member or element 5, between the body of the latter and the upstanding portion 8^b of the stand 8. Other forms of filling-engaging members or elements and supporting means, etc., therefor known in the art are adapted to be employed.

A well-known form of rocking controller is shown combined with the feeler device to enable the latter to call the change-calling mechanism into action, comprising a rock-shaft 11 that is journaled in bearings 11^a, 11^a, with which the main supporting stand 9 is provided, and an arm 12 fixed upon the inner end of the said rockshaft and connecting with the device through which a change in the operation of the loom is called. These devices, as illustrated, are of customary character, comprising a latch or dog 14 connected pivotally with an upstanding arm 15 of the usual controlling rockshaft 20, Figs. 2 and 3, the said controlling rockshaft in practice being connected operatively with the replenishing or stopping instrumentalities of the loom. The arm 12 is connected by a link 13 to the latch or dog 14, whereby the engagement of the tooth 14^b, Fig. 1, of the latch or dog by the shoulder 17^a of the vibrating weft-hammer or gooseneck 17 is controlled by the angular position of the controller-rockshaft 11. As usually is the case, the angular position of the controller-rockshaft is determined through the action of the feeler-members or elements, in accordance with the invention the controller is controlled by the special means which is explained later herein.

Referring now to the features in which the invention more especially resides:—

The filling-engaging member or element 5 bears at a point intermediate of its length a fixed vertical pivot 56, Fig. 1, upon which is rotatably mounted a secondary member 18 in the form of a small bell-crank provided with an adjustable tip 18^c, conveniently constituted of a screw, said screw projecting rearwardly from the laterally-extending arm 18^a of the said bell-crank so that its rear end is adapted to be engaged by the datum-surface carried by the lay. In the

present instance, the said datum-surface is constituted by the front face of the shuttle 4. Herein, but simply as a convenient feature of construction, tip 18^c is combined with the bell-crank by having its threaded stem 70 fitted within a threaded hole in a small plate 18^d that is attached by a screw 18^e to the said laterally-extending arm 18^a. A lug 5^a upon the filling-engaging portion 5 is provided as a stop with which the head of screw 18^e upon the secondary member 18 engages to limit the turning of said secondary member about its pivot in one direction, and thereby determine the normal presentation position of the tip 18^c. 80

The secondary member 18 is furnished with a second arm, 18^b, which may be called a transmitting arm, which acts upon and reciprocally is acted upon by a rocking control-member or lever intermediate the secondary member and the controller. In the illustrated embodiment of the invention the control-member is a horizontally-swinging bell-crank 19, which is mounted by means of a pivot 19^a upon a stationary support constituted by the cap or cover-plate 8^c. The bell-crank 19 has a rearwardly-extending arm with which transmitting arm 18^b of the secondary member 18 engages, so that through such engagement the control-member or lever keeps the secondary member in presentation position, and conversely the secondary member actuates the control-member or lever to control the controller, as when a change is called through the action 90 of the feeler-mechanism. In this illustrative embodiment of the invention, the rearwardly-extending arm of the control-member or lever is furnished with a contact-surface 19^b paralleling the path in which the filling-engaging member or element 5 reciprocates, and along which the said forwardly-projecting transmitting arm 18^b of the secondary member 18 slides in the reciprocating movements of feeler-member or element 5. The said bell-crank 19 also has a transversely-extending arm which is in engagement with a finger 20 or other form of crank-arm upon the controller-rockshaft 11. 100

In this instance the controller is actuated to keep the latch or dog 14 of the change-calling devices out of the range of action of shoulder 17^a of the weft-hammer 17 by means of a contracting spiral spring 21 that extends from the upstanding portion 8^b of the stand 8 to the transversely-extending arm of bell-crank 19. By the tension of this spring 21, the transversely-extending arm of bell-crank 19 is held normally in its forward position, and the rearwardly-extending arm is urged inwardly of the loom. In this position of bell-crank 19 the said transversely-extending arm through engagement with the pin 20 serves to keep the controller in position to uphold the latch or dog 14 110

out of range of the vibrating weft-hammer or gooseneck 17. In this position of the bell-crank 19, also, the pressure of its rearwardly-extending arm upon the extremity 5 of transmitting arm 18^b of the secondary member 18 operates to hold said secondary member in its presentation position, with the contact-tip 18^c extending rearwardly.

In the normal operation of the loom, while 10 the shuttle-contained bobbin holds a sufficient supply of weft or filling, the forward beat of the lay carries this supply of weft or filling into contact with the filling-engaging member or element 5, which enters the 15 shuttle through the customary opening 3^a in the front-plate and opening 4^a in the front-wall of the shuttle. The contact-portion or tip 18^c upon the secondary member 18 mounted upon the filling-engaging portion 5, is designed to enter within the opening 3^a in the front-plate and is adjusted to 20 make contact with the outside surface of the shuttle only when the predetermined extent of depletion of the wound mass of weft 25 within the shuttle has taken place. Hence, with an adequate supply of weft, as the filling-engaging member or element 5 is pushed forward in a feeding action it carries with it the contact-portion or tip 18^c before the 30 latter touches the shuttle-surface. As this occurs, the forwardly-extending arm 18^b of the secondary member slides forward along the contact-surface 19^b of the control-member or lever 19 without in any way turning 35 the latter about its pivot. As the lay-beam goes rearwardly, and the filling-engaging member or element 5 travels rearwardly into its presentation position again, under 40 the impulse of its spring 10, the arm 18^b of the secondary member 18 slides rearwardly along the surface 19^b of the bell-crank 19 without any change of position of such parts 45 18 and 19 about their respective pivots, and the loom continues to work without change.

As the shuttle-contained weft-supply diminishes, and the diameter of the wound mass decreases, the filling-engaging member or element 5 penetrates more and more deeply within the shuttle to reach the 50 surface of the wound mass, until it arrives at a point where the contact-portion or tip 18^c of the secondary member comes in contact with the surface of the shuttle, or other surface with which it is designed to engage.

Under the forward push of this surface, the 55 said contact-member or tip 18^c slips sideways thereupon, due to its offset position with relation to the pivot 56, so that the secondary member 18 rotates about this 60 pivot. The forwardly-extending transmitting arm 18^b of the secondary member there-by is swung outwardly, pushing outwardly the rearwardly-extending arm of bell-crank 19, and thereby swinging the transversely- 65 extending arm of the bell-crank rearwardly

against the pull of spring 21. This action leaves the controller free to rotate under the weight of the latch or dog 14, and the tooth 14^b of the latter descends into the path of oscillation of the shoulder 17^a of the 70 vibrating weft-hammer or gooseneck 17, so as to be engaged by the said shoulder and carried forward so as to operate the change-calling means to stop the loom or call a 75 change in its working.

The adjustment provided by the screw-threaded engagement of the tip 18^c with the secondary member 18 enables the devices to be set to call a change at any desired stage in the depletion of the wound mass of filling. By varying the distance of the rear end of said tip 18^c forward of the rear end of the filling-engaging member or element 5, the contact of the said tip with the datum-surface may be set to occur with a shallow 85 or a deep penetration of the filling-engaging portion into the shuttle, as may be desired.

What is claimed as the invention is,—

1. Filling-feeler mechanism for looms 90 comprising a controller for the means for calling a change, a reciprocating filling-engaging member; a horizontally-swinging datum-surface engaging member mounted on a pivot upon the filling-engaging member 95 and having a forwardly-projecting arm, and a bell-crank mounted to swing horizontally around a pivotal axis, having one arm in operative engagement with the said controller and the other provided with a 100 lateral face along which the said forwardly-projecting arm slides idly while sufficient weft remains within the shuttle, and against which said forwardly-projecting arm acts to move the bell-crank and bring about action 105 of the controller to call a change when depletion of the weft allows the datum-surface engaging member to be rotated through engagement of the datum-surface therewith.

2. Filling-feeler mechanism for looms 110 comprising a controller for the means for calling a change, a reciprocating filling-engaging member, a horizontally-swinging datum-surface engaging member mounted 115 on a pivot upon the filling-engaging member and having a transmitting arm, and a control-lever having an arm which controls the said controller and a second arm engaged slidingly with the said transmitting arm, along which second arm the transmitting 120 arm slides idly while sufficient weft remains within the shuttle, and through which the swinging movement of the said transmitting arm acts to move the control-lever to bring about action of the controller and thereby call a change when depletion of the supply 125 of weft allows the shuttle-engaging member to be rotated through engagement of the shuttle therewith.

3. Filling-feeler mechanism for looms, 130

comprising a controller for the means for calling a change, a bell-crank controlling the controller, and a reciprocating feeling-member having a filling-engaging element and a rockable datum-engaging element, the latter traveling idly lengthwise of one arm of the bell-crank during the normal working of the feeler-mechanism, rocked through impingement of the datum-surface thereagainst, and, in rocking, pressing against the said bell-crank arm to rotate the bell-crank and thereby bring about rocking of the controller to call a change.

4. Filling-feeler mechanism for looms, comprising a controller for the means for calling a change, a bell-crank controlling the controller, and a reciprocating feeling-member having a filling-engaging element and a rockable datum-engaging element, the latter traveling idly lengthwise of one arm of the bell-crank during the normal working of the feeler-mechanism, rocked through impingement of the datum-surface thereagainst, and, in rocking, pressing against the said bell-crank arm to rotate the bell-crank and thereby bring about rocking of the controller to call a change, the said datum-engaging element having a tip that is adjustable to call a change at any desired stage in the depletion of the shuttle-contained wound mass of filling.

5. Filling-feeler mechanism comprising a

feeler-member mounted to reciprocate forwardly and rearwardly, and which enters the shuttle in the feeling action and contacts with the shuttle contents, a secondary member carried by said feeler-member adapted to swing transversely, having a contact portion adapted to be engaged by a surface external of the shuttle, and also having a forwardly projecting arm, a horizontally swinging bell-crank pivoted upon a stationary support, having a rearwardly-extending arm furnished with a contact surface paralleling the path in which the feeler-member reciprocates, and along which the said forwardly-projecting arm of the contact-member slides in the reciprocating movements of the feeler-member, said bell-crank also having a transversely-extending arm, a controller for the change mechanism in engagement with the said transversely-extending arm, and a spring holding the controller in normal position and acting through the said bell-crank to keep the said secondary member normally positioned upon the feeler-member.

In testimony whereof I affix my signature in presence of two witnesses.

SIMEON S. JACKSON.
